ABSTRACT

A pipe holder and support structure is adapted to retain a smoking pipe therein while the support structure is in any desired position including a horizontal position, a generally upstanding position on a support surface, or a carried position having a support member thereof received in a pocket of a shirt or jacket with the smoking pipe on the outside of the pocket. The pipe support structure includes a backplate member having a pipe cushioning member mounted thereon and which has portions defining an elongated recess adapted to receive therein a lower portion of a stem and bowl of the smoking pipe. A pipe retaining member extends transversely of the elongated recess and is adapted to engage an upper portion of the stem to resiliently retain the smoking pipe in the elongated recess in the pipe cushioning member and to retain a heel of the bowl in engagement with an end portion of the pipe cushioning member. Opposed forces applied to opposite end portions of the pipe retaining member causes a center portion thereof to move away from the pipe cushioning member to permit the stem of the pipe to be inserted therebetween and retained therebetween upon release of the opposed forces.

Fig. 7.

PIPE HOLDER

This application is a continuation-in-part of my co-pending application Ser. No. 454,264 filed Mar. 25, 1974 and now abandoned.

The present invention relates to a portable holder for a smoking pipe which is adapted to retain a pipe therein while the tobacco holder is near a horizontal position and stem portion near an upstanding position on a support structure, or a carried position having a support member thereof received in a pocket of a shirt or jacket.

The principal objects of the present invention are: to provide a pipe holder or support structure adapted to retain a smoking pipe therein while the support structure is in any desired position including in or near a horizontal position, a generally upstanding position on a support surface, or a carried position having a support member thereof received in a pocket of a shirt or jacket with the smoking pipe on the outside of the pocket; to provide such a pipe holder adapted to permit easy placing of the pipe in the holder and easy removal of the pipe from the holder; to provide such a pipe holder constructed of material which may be manually formed or molded to conform to a curved stem portion of a smoking pipe; to provide such a pipe support structure having pipe engaging surfaces thereof formed of a material which will not mar the bowl and stem surfaces of the pipe; to provide such a pipe holder which is portable and provides a convenient, clean, and safe location for a smoking pipe; to provide such a pipe holder adapted to permit unrestricted air flow through a pipe stem and bowl; to provide such a pipe holder adapted to support the pipe in a bowl down position thereby maintaining the pipe in a preferable position when not in use; to provide such a pipe holder adapted to support the smoking pipe in or near a horizontal position which is preferred for a loaded pipe; to provide such a pipe holder having a contour adapted to receive and retain many pipe shapes; and to provide such a pipe holder which is attractive in appearance, durable in construction, convenient to use, and particularly well adapted for the proposed use.

Other objects and advantages of this invention will become apparent from the following description taken in connection with the accompanying drawings wherein are set forth by way of illustration and example certain embodiments of this invention.

The drawings constitute a part of the specification and include an exemplary embodiment of the present invention and illustrates various objects and features of the pipe support structure.

FIG. 1 is a front elevational view of a pipe support structure embodying features of the present invention and shown in a generally upstanding position on a support surface.

FIG. 2 is a side elevational view of the pipe support structure also shown in a generally upstanding position.

FIG. 3 is a rear elevational view of the pipe support structure also shown in a generally upstanding position and with portions broken away to show component parts thereof.

FIG. 4 is a top plan view of the pipe support structure shown in horizontal position preferred for a loaded pipe and with portions broken away to show component parts thereof.

FIG. 5 is a transverse sectional view taken on line 5-5, FIG. 4 and showing components in a pipe retaining position.

FIG. 6 is a transverse sectional view similar to FIG. 5 except showing the components in a pipe release position in response to opposed forces applied to opposite sides of the pipe support structure.

FIG. 7 is a side elevational view of the pipe support structure shown after being molded to conform to a smoking pipe with a curved stem and with portions broken away to show component parts thereof.

As required, detailed embodiments of the present invention are disclosed herein, however, it is to be understood that the disclosed embodiments are merely exemplary of the invention which may be embodied in various forms. Therefore, specific structural and functional details disclosed herein are not to be interpreted as limiting but merely as a basis for the claims and as a representative basis for teaching one skilled in the art to variously employ the present invention in virtually any appropriate detailed structure.

In the disclosed embodiment of the present invention, the reference numeral 1 generally designates a pipe holder or pipe support structure which is adapted to retain a smoking pipe 2 therein while the pipe structure 1 is in or near a horizontal position, a generally upstanding position on a support surface 3, or a carried position having a support member 4 thereof received in a pocket of a shirt or jacket (not shown) with the smoking pipe 2 on the outside of the pocket. The pipe support structure 1 includes a backplate member 5 (FIG. 6) having a pipe cushioning and positioning member 6 (FIG. 4) mounted thereon and which has laterally spaced elongated portions 7 and 8 defining an elongated recess 9 therebetween adapted to receive therein a lower portion of a stem 10 and a bowl 11 of the smoking pipe 2. A pipe retaining member 12 extends transversely of the elongated recess 9 and is adapted to engage an upper portion of the stem 10 to resiliently retain the smoking pipe 2 in the elongated recess 9 in the pipe cushioning member 6 and to retain a heel 14 of the bowl 11 in engagement with an end portion 15 of the pipe cushioning member 6. Opposed forces applied to opposite end portions of the pipe retaining member 12 causes a center portion thereof to move away from the pipe cushioning member 6 to permit the stem 10 of the pipe 2 to be inserted therebetween and retained therebetween upon release of the opposed forces.

The backplate member 5, when in a generally upstanding position as illustrated in FIGS. 1, 2, and 3, has upper and lower ends 16 and 17 respectively (FIG. 4). The backplate member 5 is a generally planar member and may be any desired shape with a portion thereof adjacent the upper end 16 having sufficient width to provide a hinged connection of the support member 4 thereto. The intermediate portion of the backplate member 5 has sufficient width to permit flexing thereof to permit insertion of the stem 10 of the smoking pipe 2 between the backplate member 5 and the pipe retaining member 12.

The backplate member 5 is preferably formed of a material having sufficient rigidity to receive and support the pipe 2 thereon and sufficient flexibility or resiliency whereby the backplate member 5 may be caused to assume a generally concave shape in response to inwardly directed opposed forces applied to opposite edges of the intermediate portion thereof. The back-

plate member 5 preferably has sufficient resiliency to return to the normal or generally planar shape when the opposed forces are released. It has been found that vinyl plastic in sheet form with a thickness in the nature of one thirty-second of an inch provides the desired characteristics. Vinyl plastic becomes pliable when heated and is adapted to be formed into a shape conforming to the shape of a curved pipe stem, as best seen in FIG. 7.

The pipe cushioning member 6 is illustrated as having the side portions 7 and 8 extending from the upper end 16 of the backplate member 5 when the pipe support structure 1 is in a generally upstanding position. The side portions 7 and 8 are substantially parallel to define the elongated recess 9. The illustrated pipe cushioning member 6 has a connecting portion 18 extending between and connecting lower ends of the side portions 7 and 8. The connecting portion 18 is positioned intermediate the ends of the backplate member 5 and provides a cushion for the lower portion of the bowl 11. The side portions 7 and 8 and the connecting portion 18 have peripheral edges thereof corresponding to the periphery of the backplate member 5.

The end portion 15 of the pipe cushioning member 6 extends between the connecting portion 18 and the lower end 17 of the backplate member 5. The end portion 15 is a generally U-shaped member having an open end forming an extension of the elongated recess 9 and adapted to close the lower end thereof. The end portion 15 has a greater thickness than the side portions 7 and 8 and the connecting portion 18 to thereby provide a rest for the heel 14 of the bowl 11, when the pipe support structure 1 is in a generally upstanding position on a support surface 3.

The side portions 7 and 8 and the connecting portion 18 of the pipe cushioning member 6 are preferably formed of a material which will cushion the stem 10 and bowl 11 of the pipe 2. Polyurethane foam with a density in the range of 1.25 to 1.45 pounds per cubic foot and a thickness in the nature of one-half inch has been found to provide a sufficient cushion for the pipe 2.

The end portion 15 of the pipe cushioning member 6 is also preferably formed of polyurethane foam but with a density in the nature of 3.15 to 3.75 pounds per cubic foot. The end portion 15 preferably has a thickness greater than the side portions 7 and 8 and the connecting portion 18, such as five-eighths of an inch at the deepest point thereof. The increased thickness and density of the end portion 15 relative to the side portions 7 and 8 and connecting portion 18 provides for positive support of the heel 14 of the bowl 11 when the pipe support structure 1 is in an inclined position or a generally upstanding position. The end portion 15 is shaped to have outer peripheral edges thereof adjacent the peripheral edges of the backplate member 5 and to have the upper ends of the end member 15 in abutting engagement with a lower end or edge of the connecting portion 18.

The respective portions of the pipe cushioning member 6 are suitably secured to a front side of the backplate member 5, as by a suitable adhesive, such as a contact cement, or glue.

It is desirable to provide a covering over the backplate member 5 and the pipe cushioning holder and member 6 to provide a finished appearance for the pipe holder and support structure 1 and to provide an abra-

sive resistant material to prevent scratching or marring of the surfaces of the stem 10 and the bowl 11 of the smoking pipe 2 and the support surface 3 when placed thereon. An expandable fabric, such as vinyl, soft finished leather, and polyurethane fabric having a backing of cotton stretch knit fabric, have been found to provide the desired characteristics.

A front covering 19 is suitably secured to the respective portions of the pipe cushioning member 6 and to the front side of the backplate member 5 and a rear covering 20 is suitably secured to the rear or other side of the backplate member 5, as by a suitable adhesive, such as contact cement. Peripheral edges of the front covering 19 and the rear covering 20 may extend beyond respective peripheral edges of the backplate member 5 and be suitably secured together, as by being heat welded, glued, sewed, or laced, thereby providing a finished appearance for the backplate member 5 and the pipe cushioning member 6.

A pocket 21 is provided on the rear covering 20, and tends transversely of the backplate member 5 and is formed of a strip 22 of suitable material having opposite side edges thereof suitably secured to the rear covering 20 and having open ends adjacent respective side edges of the backplate member 5. The strip 22 is preferably of the same material as the rear covering 20.

The pipe retaining member 12 is mounted on the backplate member 5 and extends transversely of the pipe positioning member 6. The pipe retaining member 12 is adapted to engage an upper portion of the stem 10 of the smoking pipe 2 thereby retaining same in the elongated recess 9 in the pipe cushioning member 6.

In the illustrated embodiment, the pipe retaining member 12 includes a front planar member 24 formed of resilient material and positioned adjacent and in engagement with the pipe cushioning member 6 and having opposite ends 25 and 26 thereof positioned adjacent respective opposite sides of the backplate member 5. The opposite ends 25 and 26 of the front planar member 24 each have spaced tubular portions thereon to define respective hinge portions.

The pipe retaining member 12 includes a rear planar member 27 formed of resilient material and positioned adjacent the other side of and in engagement with the backplate member 5 and within the pocket 21. The rear planar member 27 has opposite ends 28 and 29 thereof having respective tubular portions thereon to define respective hinge portions positioned between the tubular portions of the opposite ends 25 and 26 respectively.

Means are provided to hingedly connect the opposite ends of the front and rear planar members 24 and 27 whereby intermediate portions of the planar members 24 and 27 are spaced apart a distance corresponding to the thickness of the backplate member 5 and the pipe positioning member 6. It is preferable that the spacing between the opposite ends of the planar members 24 and 27 be slightly less than the width of the backplate member 5 so that same has an initial bow rearwardly thereof.

Opposed forces applied to the opposite ends of the planar members 24 and 27, which effects movement of the opposite ends toward each other, causes the planar members 24 and 27 to move and increase the spacing therebetween while the backplate member 5 is moving or bowing rearwardly beyond the initial rearward bow thereof. The front planar member 24 moves outwardly

from the pipe cushioning member 6 to thereby permit the stem 10 of a smoking pipe to be inserted therebetween and retained in the elongated recess 9 upon release of the opposed forces. In the illustrated structure, pins 30 and 31 are received in respective aligned tubular portions on the opposite ends of the planar members 24 and 27 to define hinges.

The planar members 24 and 27 are preferably formed of metal, such as spring steel, and it is, therefore, desirable to provide a covering for the front planar member 24 to protect the surfaces of the smoking pipe 2 when retained in the elongated recess 9. A covering 32 is preferably formed of the same material as the front covering 19 for the pipe positioning member 6. The covering 32 preferably completely encloses the front planar member 24 except for the opposite ends thereof. In the illustrated structure, the covering 32 is a sleeve, however, the material could be bonded or secured to the front planar member 24, as by a suitable adhesive.

The support member 4 has an upper end 33 thereof secured on the rear covering 20. The upper end 33 of the support member 4 is hingedly mounted on the back or rear side of the rear covering 20 adjacent the upper end 16 of the backplate member 5. The support member 4 has a lower end 34 adapted to be spaced from the lower end 17 of the backplate member 5 when the lower ends 17 and 34 are in engagement with the supporting surface 3 to position the pipe support structure 1 in an upstanding position.

The support member 4 is preferably formed of a substantially rigid material adapted to be moved between a position in engagement with the backplate member 5 or having the lower end 34 thereof spaced from the lower end 17 of the backplate member 5. The support member 4 may be formed of any suitable material, such as polyvinyl plastic, plastic impregnated paper, or the like.

The support member 4 has a suitable covering 35 preferably formed of the same material as for the coverings 19 and 20 and the covering 32 for the front planar member 24. The illustrated covering 35 has an extension 36 secured to the rear covering 20, as by a suitable adhesive, stitching, or the like to thereby provide a hinge for the support member 4.

The support member 4 preferably has a size adapted to be received within the pocket of a shirt or jacket (not shown) worn by a person. Suitable dimensions for the support member 4 have been found to be in the nature of 3 3/16 inches wide by 4 1/2 inches long.

In use, opposed forces are applied to the backplate member 5 at the opposite ends of the planar members 24 and 27 are effective to move the pins 30 and 31 toward each other, thereby causing the backplate member 5 and the rear planar member 27 to bow or flex rearwardly and the front planar member 24 to bow or flex forwardly thereby increasing the spacing between the front planar member 24 and pipe cushioning member 6 as shown in FIG. 6. A mouthpiece portion of the stem 10 is moved under the front planar member 24 and toward the upper end 16 of the backplate member 5 until bowl 11 of the pipe 2 is received in the elongated recess 9 with the heel 14 of the bowl 11 in engagement with the front covering 19 over the end portion 15. When the pipe support structure 1 is to be carried on the person, the support member 4 is inserted into a pocket with the backplate member 5 outside of

the pocket. The pipe 2 may be carried within the pipe support structure 1 with the bowl 11 down thereby providing air circulation through the pipe between the mouthpiece end and the bowl 11. When the support structure 1 is to be placed on a support surface 3 with the contents of the bowl 11 in a lighted or burning condition, the rear or lower surface of the support member 4 is preferably in engagement with the support surface 3 and the rear or backside of the backplate member 5 is in engagement with the support member 4 thereby positioning the stem 10 in a substantially level position, such as at or near horizontal, as best seen in FIG. 4. When the pipe support structure 1 is to be placed on the support surface 3 when the bowl 11 is empty, the lower ends 17 and 34 of the backplate member 5 and the support member 4 respectively are spaced apart and in engagement with the support surface 3 thereby positioning the pipe support structure in a generally upstanding position with the bowl 11 down, as best seen in FIGS. 1 and 2, to permit drainage and air circulation or breathing of the smoking pipe 2.

FIG. 7 illustrates a pipe support structure 1' after being manually molded or formed to retain therein a pipe 2' to with a curved stem 10'. The backplate member 5 is formed of material which becomes pliable when heated, therefore, the pipe support structure 1 is positioned adjacent a suitable heat source, such as an incandescent light bulb, until the backplate 5 becomes pliable. The pipe 2' is positioned within the elongated recess 9 and the stem 10' is manually maintained in engagement with the backplate member 5' and the pipe cushioning members 6' until the backplate member 5' cools sufficiently to retain a shape or contour conforming to the curved stem 10' thereby being manually molded to a shape of the curved pipe stem 10'.

Use of the pipe support structure 1' is substantially similar to use of the pipe support structure 1 illustrated in FIGS. 1 to 6 inclusive. When the pipe holder 1' is to be carried in a pocket, there will be some spacing between an upper portion of the molded or formed backplate member 5' and the pocket of the respective garment.

It is to be understood that while I have illustrated and described one form of my invention, it is not to be limited to the specific form or arrangement of parts herein described and shown.

What I claim and desire to secure by Letters Patent is:

50. 1. A pipe support structure comprising:
  - a. a backplate member having opposite sides and opposite ends;
  - b. a pipe cushioning member mounted on one side of said backplate member and having portions defining an elongated recess therein and extending longitudinally thereof and adapted to receive a lower portion of a stem and bowl of a pipe, said pipe cushioning member having opposite side edges and opposite ends; and
  - c. retaining means mounted on said backplate member and adjacent and extending transversely of the pipe cushioning member and adapted to engage an upper portion of the stem to thereby retain same in the elongated recess in the pipe cushioning member, said retaining means having end portions positioned adjacent respective opposite sides of said backplate member and adapted to have a center portion thereof move away from said cushioning

member in response to opposed forces applied to said end portions.

2. A pipe structure as set forth in claim 1 including a support member having one end thereof hingedly mounted on the other side of said backplate member adjacent one end thereof and having an other end of said support member spaced from the other end of said backplate member when said other ends are in engagement with a supporting surface to position said backplate member and said support member in a generally 10 upstanding position.

3. A pipe support structure as set forth in claim 1 wherein:

- a. said backplate member is a resilient member 15 whereby opposed forces applied to the opposite sides of said backplate member causes same to assume a generally transverse concave shape; and
- b. said retaining means includes a planar member formed of resilient material and having said opposite end portions thereof each mounted adjacent a 20 respective one of the opposite edges of said backplate member whereby the opposed forces causes said planar member to assume a generally concave shape in opposed relation to the concave shape of said backplate member to thereby permit the stem of a pipe to be inserted therebetween and retained therebetween upon release of the opposed forces.

4. A pipe support structure as set forth in claim 1 wherein said retaining means includes:

- a. a first planar member formed of resilient material and positioned adjacent said pipe cushioning member and having opposite end portions thereof adjacent respective opposite sides of said backplate member; 35
- b. a second planar member formed of resilient material and positioned adjacent the other side of said backplate member and having opposite end portions thereof adjacent respective opposite sides of said backplate member; and 40
- c. means hingedly connecting the opposite end portions of said first planar member to respective opposite end portions of said second planar member whereby intermediate portions of said first and second planar members are spaced apart and opposed 45 forces applied to said opposite end portions thereof which effects movement of the opposite end portions toward each other causes said first planar member to move outwardly from said pipe cushioning member to thereby permit the stem of a pipe to be inserted therebetween and retained therebetween upon release of the opposed forces.

5. A pipe support structure as set forth in claim 1 wherein:

- a. said recess defining portions of said pipe cushioning member include first and second portions positioned in laterally spaced relation and each extending longitudinally of said backplate member and from one end of said backplate member to adjacent the other end thereof to define the elongated recess therebetween; 60
- b. said pipe cushioning member has end portion extending between said first and second portions and positioned adjacent the other end of said backplate member to define an end for the elongated recess; and 65

c. said pipe cushioning end portion is positioned to be engaged by a heel portion of the bowl of a pipe to thereby retain same in said elongated recess.

6. A pipe support structure as set forth in claim 5 wherein:

- a. said backplate member is a resilient member whereby opposed forces applied to the opposite sides of said backplate member causes same to assume a generally concave shape; and
- b. said retaining means includes a planar member formed of resilient material and positioned in overlying relation with said pipe cushioning member and having opposite end portions thereof each hingedly supported adjacent a respective one of the opposite edges of said backplate member whereby opposed forces applied to the opposite end portions of said planar member and to the opposite sides of said backplate member causes said planar member and said backplate member to each assume a generally concave shape in opposed relation one to the other to thereby permit the stem of a pipe to be inserted therebetween and retained therebetween upon release of the opposed forces.

7. A pipe support structure as set forth in claim 6 wherein said retaining means includes:

- a. a second planar member formed of resilient material and positioned adjacent the other side of said backplate member and having opposite end portions thereof adjacent respective opposite sides of said backplate member; and
- b. means hingedly connecting the opposite end portions of said first named planar member to respective opposite end portions of said second planar member whereby intermediate portions of said first named and second planar members are spaced apart and opposed forces applied to the opposite end portions thereof which effects movement of the opposite end portions toward each other causes said first named planar member to move outwardly from said pipe cushioning member to thereby permit the stem of a pipe to be inserted therebetween and retained therebetween upon release of the opposed forces.

8. A pipe support structure comprising:

- a. a backplate member having opposite ends and opposite sides;
- b. a pipe cushioning member mounted on one side of said backplate member and having portions defining an elongated recess therein and extending longitudinally from one end of said backplate member and adapted to receive a lower portion of a stem and bowl of a pipe;
- c. retaining means mounted on said backplate member and extending transversely of the pipe cushioning member and adapted to resiliently engage an upper portion of the stem of said pipe to thereby retain same in the elongated recess in said pipe cushioning member, said retaining means having end portions positioned at respective opposite edges of said backplate member and adapted to have a center portion thereof move away from said cushioning member in response to opposed forces applied to said end portions; and
- d. a support member having one end thereof hingedly mounted on the other side of said backplate member adjacent one end thereof and having the other end of said support member selectively movable to

a position spaced from the other end of said backplate member when said other ends are in engagement with a supporting surface to position said backplate member and support member in a generally upstanding position. 5

9. A pipe support structure as set forth in claim 8 wherein:

- a. said recess defining portions of said pipe cushioning member include first and second portions positioned in laterally spaced relation and each extending longitudinally of said backplate member and from one end of said backplate member to adjacent the other end thereof to define the elongated recess therebetween; 10
- b. said pipe cushioning member has an end portion extending between said first and second portions and positioned adjacent the other end of said backplate member to define an end for the elongated recess; 15
- c. said end portion is positioned to be engaged by a heel portion of the bowl of a pipe to thereby retain same in said elongated recess; 20
- d. said first and second portions of said pipe cushioning member are each formed of resilient material to provide a cushion for the stem and bowl of the pipe; and 25
- e. said end portion of said pipe cushioning member is formed of resilient material to provide a cushion for the heel portion of the bowl of the pipe.

10. A pipe support structure as set forth in claim 9 wherein:

- a. said backplate member is a resilient member whereby opposed forces applied to the opposite sides of said backplate member causes same to assume a generally concave shape; and 35
- b. said retaining means includes:
  - 1. a planar member formed of resilient material and positioned in overlying relation with said pipe cushioning member and having opposite end portions thereof each hingedly supported adjacent a respective one of the opposite edges of

said backplate member whereby opposed forces applied to the opposite end portions of said planar member and to the opposite sides of said backplate member to each assume a generally concave shape in opposed relation one to the other to thereby permit the stem of a pipe to be inserted therebetween and retained therebetween upon release of the opposed forces;

- 2. a second planar member formed of resilient material and positioned adjacent the other side of said backplate member and having opposite end portions thereof adjacent respective opposite sides of said backplate member; and

- 3. means hingedly connecting the opposite end portions of said first named planar member to respective opposite end portions of said second planar member whereby intermediate portions of said first named and second planar members are spaced apart and opposed forces applied to the opposite ends thereof which effects movement of the opposite end portions toward each other causes said first named planar member to move outwardly from said pipe cushioning member to thereby permit the stem of a pipe to be inserted therebetween and retained therebetween upon release of the opposed forces.

11. A pipe support structure as set forth in claim 10 wherein:

- a. said second planar member is secured to said backplate member to substantially prevent relative movement therebetween; and
- b. said first named planar member is enclosed within covering material to substantially prevent damage to surfaces of the stem of the pipe.

12. A pipe support structure as set forth in claim 8 wherein said backplate member is formed of material which becomes pliable in response to being heated whereby said backplate member may be manually molded to a shape of a curved pipe stem.

* * * * *
